United States Patent

Des. 238,223
Patented Dec. 30, 1975

238,223

SOFA OR SIMILAR ARTICLE

Richard I. Brooks, North Hollywood, Calif., assignor to Kroehler Mfg. Co., Naperville, Ill.

Filed July 30, 1974, Ser. No. 493,035

Term of patent 14 years

Int. Cl. D6—01

U.S. Cl. D6—63

Fig. 1.

Fig. 2.

Fig. 3.

FIG. 1 is a front perspective view of a sofa or similar article showing my new design;

FIG. 2 is a side perspective view thereof; and

FIG. 3 is a rear elevational view thereof.

The side of my sofa or similar article opposite that shown in the figures is symmetrically reverse but otherwise identical.

I claim:

The ornamental design for a sofa or similar article, as shown and described.
